UNITED STATES PATENT OFFICE.

GEORGE E. BARTHOLOMEW, OF CINCINNATI, OHIO, ASSIGNOR OF ONE-HALF
TO EDWARD R. EDWARDS, OF SAME PLACE.

SPRING-GEAR FOR VEHICLES.

SPECIFICATION forming part of Letters Patent No. 446,656, dated February 17, 1891.

Application filed December 9, 1890. Serial No. 374,015. (No model.)

To all whom it may concern:

Be it known that I, GEORGE E. BARTHOLOMEW, a citizen of the United States, and a resident of Cincinnati, in the county of Hamilton and State of Ohio, have invented certain new and useful Improvements in Spring-Gear for Vehicles, of which the following is a specification.

The object of my invention is to provide a light cheap spring-gear for vehicles.

It consists in the peculiar combination and arrangement of the parts, all of which will be first fully described in connection with the accompanying drawings, and will then be particularly referred to and pointed out in the claims.

Referring to the drawings, in which like parts are indicated by similar reference-letters wherever they occur throughout the various views, Figure 1 is an inverted plan view of the front part of a spring-wagon provided with my improvements. Fig. 2 is a vertical longitudinal sectional view of the same, taken through line xx of Fig. 1. Fig. 3 is a plan view 25 of the front part of a wagon with my invention applied in a modified form. Figs. 4 and 5 are longitudinal central vertical sections of my preferred form of gear (shown in Figs. 1 and 2) with a modified form of brace. Fig. 6 is an inverted plan view of the front part of 30 a wagon with my improvement applied to a half platform-gear. Fig. 7 is a longitudinal central vertical section of the same. Fig. 8 is a vertical transverse section of the same.

In the forms of my invention shown in Figs. 1 to 5, inclusive, the body and fifth-wheel device are coupled to the front axle by quarter-elliptic springs, while in the forms shown in Figs. 6, 7, and 8 platform-springs are employed for the same purpose.

Referring first to the preferred form of my invention, (shown in Figs. 1 and 2,) A represents the body-bottom; a , a cross-bar secured underneath it; $B B'$, a pair of quarter-elliptic 45 springs, and C the front axle.

D is a spring bar or plate, made either of hard wood or metal, or of wood faced with metal. This bar is pivoted underneath the cross-bar a on the king-bolt E . The heavy 50 ends of the springs B are bolted rigidly to this

pivoted spring-bar and the light ends are clipped to the front axle.

To hold the pivoted spring-bar D firmly against the body cross-bar a , as well as to relieve the king-bolt from strain, I provide a 55 strap-metal yoke F , the ends of which are bolted firmly to the body-bottom, from which points it arches across the spring-bar D and is perforated to pass the screw-threaded end of the king-bolt. I also provide a metal sleeve 60 G , which has an annular flange g below its upper end, upon which the spring-bar rests. The yoke F bears against the lower end of this sleeve, and the king-bolt passes through the bar a , sleeve G , and yoke F , and has a nut on 65 its screw-threaded lower end to hold the parts together. I have shown the rear part of the bar or yoke F bifurcated, and prefer to use it this way for greater strength; but it may be made straight, as indicated by dotted line. 70

Instead of the curved metal-strap yoke F , (shown in Figs. 1 and 2,) the rigid brace F' (shown in Fig. 4) may be employed. This consists of a wooden central bar strengthened by two metal straps f , one above and one below. The king-bolt passes centrally through this brace, and the ends of the brace are secured to the wagon-body by bolts f' and intervening stay blocks or collars f'' . 75

In the modification shown in Fig. 5 a portion of the brace F is cut away in front of the king-bolt and a metal brace f^3 underlaps its forward end and is perforated to pass the king-bolt. From the king-bolt the metal brace curves upward to the spring-bar, to which its 80 forward end is rigidly secured.

In the modification shown in Fig. 3 the king-bolt is relieved from strain by a spring-steel strap-bar F^2 and brace-bars f^4 of the same material. The bar F^2 has its rear end 85 turned to form an eye to receive a stud-bolt f^5 , which is secured in and projects down from the rear part of the body-bottom. The brace-bars f^4 have their front ends bolted firmly to the front of bar F^2 , from which point they 90 diverge to near the rear edge of the spring-bar D , to which they are firmly secured by the clips f^6 , which are preferably seated in notches formed in the edge of the braces. 95

In Figs. 6 to 8, inclusive, I illustrate my 100

improvements applied to a platform-gear. The swivel-bar D in this case crosses the bar *a* transversely instead of being parallel with it. The yoke E³ is substantially the same as shown in Figs. 1 and 2 and occupies the same position with relation to the swivel-bar. I also employ the same flanged sleeve G and have metal rub-plates to reduce friction between the swivel-bar D and bar *a*.

10 B' are the customary platform-springs clipped upon the front axle, and H a semi-elliptic spring, of ordinary construction, shackled to the forward ends of the springs B' in the usual manner. The rear ends of the springs B' are connected to a cross-bar I by spring-shackles. The forward end of the swivel-bar D is bolted or clipped on top of the semi-elliptic spring H, and its rear end is similarly secured centrally to the cross-bar I. This 15 arrangement of coupling the front axle to the spring-bar D by means of the front springs allows the wagon to make a very short or quick turn, and the brace bar or yoke, assisted by the king-bolt, keeps the swivel-bar against 20 the cross-bar *a*, prevents rattling when passing over a rough road, and relieves the king-bolt from strain.

25 In all of the forms shown I prefer for economy to couple the rear axle to the body 30 by the quarter-elliptic springs diverging like the front springs B from their point of attachment to the body to the axle; but other well-known forms of springs may be substituted for them without changing the devices 35 shown for coupling the front axle to the body.

What I claim is—

1. In a spring-gear for coupling the front axle to the body, the combination of the spring-

bar D, pivoted underneath the body back of its front end, a brace to hold the spring-bar 40 to the body and relieve the king-bolt from strain, and springs secured to the spring-bar and front axle, substantially as shown and described.

2. In a spring-gear for coupling the front 45 axle to the body, the combination of the spring-bar D, pivoted underneath the body back of its front end, a brace to hold the spring-bar to the body and relieve the king-bolt from strain, and the quarter-elliptic springs B, hav- 50 ing their heavy ends rigidly secured to the spring-bar and their light ends clipped to the front axle, substantially as shown and described.

3. The combination, substantially as hereinbefore set forth, of the body A, having cross-bar *a*, the spring-bar D, pivoted under said bar *a*, the brace passing transversely across the spring-bar and having its ends secured to the wagon-bottom, the king-bolt E, passing 60 through the bars and brace, and the springs secured to the spring-bar and front axle, substantially as shown and described.

4. The combination of the body having cross-bar *a*, the axles, the spring-bar D, the 65 flanged sleeve, the king-bolt E, the bar D, pivoted to the bar *a*, the brace secured to the body and crossing the spring-bar to hold it against the bar *a* and relieve the king-bolt, and the springs coupling the spring-bar and 70 front axle, substantially as shown and described.

G. E. BARTHOLOMEW.
